DESIGN FOR A HAND BAG

Keriacos Thucaky, Haverhill, Mass.

Application February 14, 1935, Serial No. 55,419

Term of patent 7 years

To all whom it may concern:

Be it known that I, Keriacos Thucaky, a citizen of the United States, residing at Haverhill, in the county of Essex and State of Massachusetts, have invented a new, original, and ornamental Design for Hand Bag, of which the following is a specification, reference being had to the accompanying drawing, forming part thereof.

Figures 2 and 3 are opposite edge elevational views of the same.

I claim:

The ornamental design for a hand bag, as shown.

KERIACOS THUCAKY.
